UNITED STATES PATENT OFFICE.

FRANK A. CARPENTER, OF WASHINGTON, DISTRICT OF COLUMBIA.

ROLLER-SCREEN FOR CAR-WINDOWS.

SPECIFICATION forming part of Letters Patent No. 714,362, dated November 25, 1902.

Application filed September 4, 1902. Serial No. 122,061. (No model.)

To all whom it may concern:

Be it known that I, FRANK A. CARPENTER, a citizen of the United States, residing at Washington, in the District of Columbia, have invented certain new and useful Improvements in Roller-Screens for Car-Windows; and I do hereby declare the following to be a full, clear, and exact description of the invention, such as will enable others skilled in the art to which it appertains to make and use the same.

My invention relates to window-screens, has special reference to the application of roller-screens to car-windows for the protection of passengers from the annoyance and discomfort produced by cinders from the locomotive-engine entering open windows, and consists in certain improvements in construction, which will be fully disclosed in the following specification and claims.

In the accompanying drawings, which form part of this specification, Figure 1 represents a front elevation of a window in closed position; Fig. 2, a like view showing the window raised and a screen in position below the window; Fig. 3, a like view, partly in section, to show the means for securing the screen to the window; Fig. 4, a vertical transverse section on line 4-4, Fig. 3; and Fig. 5, an enlarged detail view showing the means for securing the screen to the window.

Reference being had to the drawings and the designating characters thereon, 1 indicates a window-sash; 2, the vertical sides of the casing; 3, the facing on the sides of the casing; 4, the outer window-sill, having a slot 5 therein; 6, the inner sill; 7, a pocket in the frame; 9, a removable panel on the inside of the car, affording ready access to the pocket 7 for adjustment of roller 10, on which the screen 11 is rolled, and the roller 10 is provided with a spring 12 for winding the screen.

On the lower edge of bottom rail of the sash is a metallic shoe or bar 13, having slots 14 for the reception of locking members on the screen, and inclosed in the sash-rail are oppositely-arranged bolts 15 16, longitudinally movable in bearings 17 18, and on each of said bolts between the bearings 17 18 is a coiled spring 19, one end of which bears against a

pin 20, while the opposite end of spring bears 50 against the outer bearings 17 to hold the bolt in engagement with the shoulder or catch 21 on each locking member 22, which members are secured to a metallic bar 23 on the upper end of the screen 11. The inner ends of the 55 bolts 15 and 16 are provided with upwardly-curved arms 24, which enter the opening or recessed pocket 25 in the handle 26 for raising the window and are drawn toward each other to release the bolts from the locking 60 members 22 when it is desired to raise the window without raising the screen.

The sash is provided with the usual spring-catch 27, which engages the stop 28 to support the window in raised position. 65

The normal position of the bolts 15 16 is in engagement with the shoulders 21 on the locking members 22, so that as a passenger raises a window provided with my screen the screen is drawn up with the window and serves to 70 prevent the entrance of cinders or other objectionable matters, and as the window is lowered the roller 10 winds the screen 11 thereon.

Should it be desired to have the window-opening unobstructed by the screen, the bolts 75 15 16 are drawn toward each other, and thus releasing the shoulders or catches 21, when the window can be raised without drawing the screen up with it; but when the window is closed the locking members 22 automatically engage the bolts 15 16 and place the screen 80 in condition to be raised with the window.

Having thus fully described my invention, what I claim is—

1. A window-sash having slots in the lower 85 edge of the bottom rail of the sash, a handle in said bottom rail for raising the sash and having an opening or recessed pocket therein, and a locking device composed of oppositely-arranged spring-controlled bolts contained in 90 said rail and whose adjacent inner ends are in the opening or pocket of said handle; in combination with a roller-screen having a transverse bar on its upper end provided with projecting members engaging said slots and 95 said locking device.

2. A window-sash having a metallic shoe on the lower edge of the bottom rail provided

with slots, a handle in said bottom rail having an opening or recessed pocket therein, and oppositely-arranged spring-controlled horizontal bolts contained in said rail and 5 whose inner and adjacent ends are provided with curved arms contained in the pocket of said handle; in combination with a screen having a transverse bar on its upper edge pro-

vided with projecting members engaging said slots and said bolts.

In testimony whereof I affix my signature in presence of two witnesses.

FRANK A. CARPENTER.
